POUCH FOR TOBACCO AND SMOKING ACCESSORIES

John A. McMananey, 6 Highland Ave.,
High Bridge, N.J. 08892

Filed Sept. 13, 1973, Ser. No. 396,728

Term of patent 14 years

Int. Cl. D27—06

U.S. Cl. D27—44

FIG. 1

FIG. 2

FIG. 1 is a front right perspective view of a pouch for tobacco and smoking accessories showing my new design;

FIG. 2 is a front left perspective view on a reduced scale; and

FIG. 3 is a rear elevational view thereof.

I claim:

The ornamental design for a pouch for tobacco and smoking accessories, substantially as shown and described.
